UNITED STATES PATENT OFFICE.

WELLINGTON W. MUIR, OF LOCKPORT, NEW YORK.

COOLING SYSTEM.

Application filed November 28, 1921. Serial No. 518,379.

The present invention has reference to cooling systems for internal combustion engines of the type wherein a fluid is employed as the cooling agent.

5 One of the objects of the invention is the provision of a new and improved cooling system for internal combustion engines wherein the generation of steam and vapor and its condensation is employed in said system.

10 Another object of the invention is the provision of a new and improved arrangement of mechanism for returning the condensed fluid to the liquid cooling system.

15 Other and further objects and advantages of the invention will appear as the description proceeds.

In the drawings,

20 Figure 1 is a vertical sectional view, more or less diagrammatic, of a preferred embodiment of the invention, parts in elevation and parts broken away;

Figure 2 is a vertical section through an auxiliary tank shown in Figure 1;

25 Figure 3 is a view similar to Figure 1 showing a modified form of the device;

Figure 4 is a detail view showing a modified form of vent arrangement for the vacuum tank;

30 Figure 5 is a view of another modified construction in which the auxiliary or vacuum tank is replaced by a shaft driven pump; parts being shown in section;

Figure 6 is a detail view of a modified form of vent arrangement;

35 Figures 7 and 8 are sectional views of modified forms of the device shown in Figure 3; and

Figure 9 is a detail view of an attachment.

40 Referring now more particularly to Figures 1 and 2 of the drawings the reference numeral 1 indicates an internal combustion engine having the water jacket 2 associated therewith, as is usual in such constructions. The water jacket 2 is supplied with water or other cooling fluid from the chamber or header 3 of the radiator 10 through the passage 4 which connects the header 3 with the lower portion of the water jacket 2, the return of the water taking place through a conduit or passage 5. As shown, the overflow opening of the passage 5 is above the level 6 of the liquid in the upper chamber, but the construction may be otherwise.

The chamber 3 is variously designated herein as a chamber, header or water hopper.

60 In order to prevent the local formation of steam in undesirable or dangerous quantities in the jacket 2 of the engine, it is desirable though not absolutely necessary to provide power-operated means for circulating the cooling fluid therethrough. Any suitable mechanism may be employed for this purpose. As shown on the drawings, 65 a pump 7 located in the passage 4 and operated from the fan shaft 7' is employed for this purpose.

70 The chamber 3, passage 4, the water jacket 2, and the passage 5 constitute what may be considered the main circulatory system. When the free end of the pipe 5 is arranged to extend above the level of the liquid in the header 3 as shown in the drawing, the main circulatory system may be considered 75 as being a non-continuous or an interrupted one and as a result of this construction, whether or not a pump be employed, there will be no circulation of the cooling fluid 80 while the engine is at rest, consequently it will take a relatively long time to cool the water within the jacket and the engine will remain warm for a comparatively long period after it stops running.

85 Associated with the chamber 3 is a radiator, or radiator core or condenser 10 of any suitable construction. This radiator may be located at any convenient point relative to the engine. As shown, it occupies the usual position in front of the engine.

90 Under certain conditions, it is desirable that the radiator be so arranged that no liquid circulates through it. Any suitable arrangement of mechanism may be employed for this purpose. One form of mechanism 95 for accomplishing this without the use of valves is shown on the drawing wherein the passage 11 leading into the radiator has its upper end extending above the level of the liquid system. The lower end of the pipe 11 100 may be attached at any convenient point to the radiator, as at one end thereof. As shown, it is attached to the upper end of the radiator. This arrangement permits only vapor or steam to enter the radiator core. 105 Moreover, this arrangement not only permits the engine to operate at higher temperatures and consequently more efficiently, but also permits the employment of a smaller 110 amount of the cooling fluid than is common-

ly used, together with a considerable reduction in the size of the radiator, because of the greater difference in temperature between the air and the radiator core which is 5 conducive to a greater transference of heat between the two. Moreover, since vapors and steam formed in the system are condensed and returned thereto, it not only permits the use of a smaller amount of the cooling fluid but also prevents the escape of any volatile anti-freezing mixture that may be employed. The lower end of the core 10 is provided with, or connected into, a lower chamber or header 12 for receiving the condensed fluid.

Suitable provision is made whereby the condensed fluid is returned to the body of the cooling liquid. Any suitable means may be provided for this purpose. As shown in 20 Figures 1 to 4 pump mechanism, in the form of an auxiliary tank or chamber arrangement, is employed which is in communication with the header 12 through the pipe or passage 13. This chamber 14 may be of any 25 suitable construction. As shown, this chamber is formed of two cup-shaped stampings 20 and 21 joined together and to the chamber 3 by the flanges 22 in any suitable way.

The upper portion of the chamber is provided with a valve support 23 secured in the top of the chamber. As shown, this support is provided with an aperture or vent 24 in communication with the atmosphere. The valve support may, if desired, be provided 35 with a lateral extension 24' having an aperture therein in communication with the aperture or vent 24. By this arrangement the aperture or vent opens laterally into the air and dirt and dust is not quite so likely 40 to enter and stop up the same. This extension may, of course, be omitted if desired.

The lower portion of the chamber has an outlet passage 25 with a dump valve 26 preferably located above the level 6 of the liquid and also preferably of the normally closed type. The valve 26 may be provided with suitable means, such as the counterweight 26', for normally seating the valve. Mounted 50 within the chamber 14, as by means of the brackets 26^a, is a float chamber 27 open at the top and provided near its bottom with an opening or openings 28; and suspended in the float chamber in any suitable manner 55 is a relatively large float, the construction of which may be varied widely. In the form shown, it comprises the cylindrical body 30 and the heads 31 soldered or otherwise connected thereto.

60 The chamber 14 is provided with a vent passage which may open into the chamber or header 3. As indicated in Figures 1 and 2, a passage or conduit 32 has one end secured in the wall of the header or chamber and its 65 other end extending into the chamber 14 is

secured in the valve support in communication with the aperture 32'. In the form shown, the apertures 24 and 32' are in vertical alignment and are adapted to be alternately opened and closed by a double valve 70 35, but here again the construction may be varied, that shown being preferred largely because of its low cost. The valve is operated from the float in any suitable manner. As shown, the valve has an elongated slot 75 37 for receiving the bail 36, which extends through the slot 45 of the valve guide 55. For convenience in manufacturing and assembling the device, the guide 55 may be bifurcated or slotted from its top downwardly 80 for receiving the bail 36, the lower end of the slot being indicated by the dotted line 45^a, Figure 4.

The pipe or passage 11, radiator core 10, the lower radiator chamber or header 12, 85 pipe or passage 13, and the auxiliary chamber 14 constitute what might be termed the auxiliary circulatory system. The main circulatory system and the auxiliary system may be together considered as constituting 90 the cooling system for the engine.

It is desirable that the filling passage 38 be connected into the chamber 3 from the side and that its upper end be so located as to preclude the filling of the chamber 3 above 95 the level 6.

In operation, when the engine starts the pump will cause a circulation of the cooling liquid in the main circulating system which will prevent "hot spots" and the consequent 100 undesirable formation of steam at local points only. As a matter of fact, there is very little cooling effect until the liquid in the main circulatory system becomes heated well toward the boiling point—in other 105 words, the engine on starting is brought quickly to a temperature which gives efficient operation. Thereafter, the vapor and steam escaping into the chamber 3 finds its way through the passage 11 into the passages 110 of the core 10 where it is quickly condensed. Under these conditions the dump valve 26 is closed and there is little or no liquid in the vacuum chamber, therefore the float is 115 at its lower limit of movement and the chamber 14 is in communication with the atmosphere through the vent or aperture 24, thus permitting the escape of air entrapped in the system or given up by the liquid when it is heated. The condensed fluid soon seals the lower end of the pipe or passage 13 and then when the pressure of the steam in the radiator becomes sufficient it will force the condensed fluid in the header 12 through the 120 passage 13 into the space surrounding the float chamber 27 which it finally overtops, but before this latter takes place, a sufficient quantity of liquid will have entered the float chamber through the openings 28 to largely overcome the displacement of the 125 130

float from which it follows that when the liquid overflows the upper edge of the valve chamber it will cause the float to rise rapidly to effect a very prompt and positive shifting 5 of the valve. The shifting of the valve 35 will close the vent 24 and open the passage 32 and the pressure in the chamber or auxiliary chamber 14 and the header 3 becoming equalized the liquid in the passage or pipe 13 will cease to flow into the auxiliary chamber 14 and the liquid therein will be discharged through the outlet passage 25 into the header 3. This operation will be repeated indefinitely in accordance with the 15 rate of steam formation.

In the form of the device shown in Figure 3 the vacuum tank principle is employed for transferring the condensed fluid from the lower radiator chamber 12 to the upper 20 radiator chamber or header 3. In other words, in this form of the device, the suction of the engine is employed for accomplishing this liquid transference. The arrangement of the device differs from that 25 shown in Figure 1 in that the chamber 14 which may be termed a vacuum tank in this form of the device, is provided with a suction pipe 39 which is connected to the lateral extension 24' and is in communication with 30 any suitable source of suction, such as the intake passage of the engine, or an air pump of any kind, whether shaft driven or not or of any of the various types of air exhausting devices whether or not they depend 35 for their operation on the movement of liquids, exhaust gasses or other fluids.

In order to provide for the escape of air that may become entrapped in the system the upper portion of the lower radiator 40 chamber or header 12 may, if desired, be provided with an upwardly extending vent pipe 40. This pipe may be omitted, if desired.

In the operation of this form of the device, 45 steam formed in the system will be condensed in the radiator 10. Assuming, now, that the float 30, see Fig. 2, is at the lower limit of its travel, the vent 24 will be open and the suction of the engine will exhaust 50 the air in the chamber 14 thus drawing the condensed fluid from the lower radiator chamber 12 into the chamber 14 thus causing the float 30 to rise and cause the valve 35 to close the vent 24 and open the passage 32, 55 which operation will permit the equalization of the pressure and permit the liquid to dump into the chamber or header 3, similar to the operation of the usual fuel vacuum tank. This operation will be repeated so 60 long as the engine is running and the level of the liquid in the chamber 12 is above the opening that leads into the pipe or passage 13.

In Figure 4 is shown a modified arrangement 65 adapted for use with a system like

that illustrated in Fig. 3. In this form of the device the vent 41 is in communication with atmosphere instead of in communication with the chamber 3 as shown in Figure 2. The operation of this device is similar 70 to the form shown in Figure 2.

The modification shown in Figure 5 differs from that just described in that a pump 42 in communication with the lower radiator 75 chamber 12' and separate from the pump 7, is employed to return the condensed liquid to the liquid circulatory system, the return pipe 43 opening into the chamber 3 preferably at a point above the level 6 of the liquid. In this case it is desirable to provide a vent 80 passage 44 for the lower header 12' to permit the escape of trapped air, and to allow the escape of steam under exceptional circumstances.

In Figure 6 is shown a modification of 85 the arrangement of the air vent in the chamber 14. Under certain conditions, as when the arrangement is such that the steam that enters the chamber 14 to equalize the pressure 90 therein is condensed by the incoming water of condensation or is condensed by other means, after the passage 32 is closed, it is not necessary that the vent be open to the atmosphere. Moreover, under such conditions the system may be operated at higher 95 pressures than obtains in the open air vent system. This may be accomplished by providing a safety valve of any suitable form in the vent.

As shown on the drawing, it may be accomplished by substituting the valve support 23^a for the support 23 shown in Fig. 2. The threaded stem 46 is shortened so that the bail 36 will engage the abutment 47 and prevent the valve 35 from closing the vent 24^a. The upper end of the vent 24^a is enlarged to form a valve seat on which is seated the ball valve 48. The valve 48 is normally held on its seat by means of the spring 49 which is adjustably held under compression by the nut 50 which has an opening therethrough. The valve 48 is adapted to open and relieve the pressure within the chamber 14, when the same rises above a 110 predetermined amount.

If desired, means may be provided for relieving the external or atmospheric pressure on the chamber 14 and radiator due to the condensation of the steam within the same incident to the non-operation of the engine. As shown in Figure 6, this is accomplished by providing the valve support 23^a with a lateral conduit 51 having a restriction portion to form a seat for the spring 52. The outer end of the conduit 51 is internally threaded to receive the apertured screw-threaded plug 53 which is provided with a valve seat at its under end within which the ball valve 54 is normally held by the 120 springs 52. The compression of the spring 125 52 holds the ball valve 54 in its seat. The 130

52 may be varied by turning the nut 53. The parts may be so adjusted that when the internal pressure falls below a predetermined minimum the valve 54 will open 5 against the compression of the spring 52 and relieve the pressure.

In Figures 1 to 4 the tank or chamber 14 is shown as having its lower end extending down into the chamber or header 3 but it 10 is to be understood that this tank or chamber may be separate from said header and located at any convenient point above the level of the water in said header as shown in Figures 7 and 8.

15 When the tank or chamber 14 is mounted independently of the header 3, it is, of course, necessary to provide means whereby the liquid may be conducted from said tank or chamber to the header 3. Any suitable 20 means may be employed for this purpose. This means is clearly illustrated in the modified form of the device shown in Figures 7 and 8. In these figures a receptacle 56 is shown as being secured to the lower end of 25 the tank 14 and is adapted to receive the liquid from said tank. A conduit 57 connected to the bottom of the receptacle 56 is secured in the wall of the header 3 for conducting the liquid into said header.

30 The form of the device shown in Figure 7 differs further from that shown in Figures 2 and 3 in that the lower chamber or header 12 is not provided with an air vent. By this arrangement, the suction of the engine 35 through the conduit 39 causes this system to operate at sub-atmospheric pressures.

This arrangement is, therefore, advantageous where it is desirable to operate the engine at lower temperatures and at the 40 same time employ steam as one of the cooling agents.

The device shown in Figure 8 differs from that shown in Figures 2 and 3 in that the tank 14 is separate from the header 3 and 45 located above the level of the water therein. Where the tank or chamber 14 is secured in such a manner that steam is formed therein as is shown in Figure 3, the suction of the engine will remove the steam with a consequent loss of the cooling fluid which is 50 very undesirable, especially when volatile anti-freezing mixtures are employed. In order to overcome this difficulty the tank or chamber 14 is separated from the header 3 55 as shown in this figure and is so located that it is not materially effected by either the heat from the cooling fluid or the heat of the engine. It may be also desirable that means be provided whereby the liquid in the 60 main system may be caused to circulate through the radiator along with the steam and vapor.

Any suitable mechanism may be provided for accomplishing this function. A simple 65 device for accomplishing this is shown in

Figure 9. It is in the form of an attachment that may be applied to the upper end of the pipe or passage 11 in the various forms shown. It consists of a small inverted cup member 58 having an attaching collar 70 59 rigidly attached thereto which is provided with a set screw 60 for securing said member in adjusted position over the upper end of the pipe or passage 11 in such a manner that its lower edge will remain below 75 the level of the liquid in the upper chamber or header 3.

The upper or closed end of the chamber 58 is provided with a small opening or perforation 61 whereby vapor and steam may 80 pass from the upper chamber or header 3 down into the radiator. When the steam is generated so rapidly in the engine jacket that it cannot pass through the aperture 61 rapidly enough to prevent increase in pressure 85 within the upper chamber or header 3 or when for any reason the difference in pressure between the headers or chambers 3 and 12 reaches a predetermined point, whether by increasing the pressure in the upper 90 header or decreasing that in the lower one, the water in the upper header or chamber 3 will be forced up into the cup or chamber 58 and be permitted to escape into the pipe or passage 11 from whence it will pass with 95 the steam through the radiator and be cooled thereby.

The size of the opening or perforation 61 in the cup or chamber 58 will, of course, be varied to meet the particular requirements 100 and operating conditions of the same or different engines, as desired. In practice, different cups provided with different sized openings or perforations are provided.

It is thought from the foregoing taken in 105 connection with the accompanying drawings that the construction and operation of my device will be apparent to those skilled in the art, and that various changes in size, shape and proportion and details of construction may be made without departing 110 from the spirit and scope of the appended claims.

I claim:

1. The process of cooling internal combustion engines which consists in providing a liquid cooling circuit about the engine having a liquid and vapor chamber at its upper portion, positively drawing the vapor from said chamber downwardly through a radiator to 120 condense the same in a liquid chamber at the base of said radiator and positively returning the liquid from said liquid chamber directly to the top of the liquid and vapor chamber in said first mentioned circuit. 125

2. A cooling system for internal combustion engines comprising a primary cooling circuit including a liquid and vapor chamber at the upper portion thereof, a secondary cooling circuit having a vapor chamber at 130

its upper portion, a common enclosing casting for said chambers, a radiator in said secondary circuit communicating with and disposed below said vapor chamber, a liquid chamber at the bottom of said radiator and positive means for returning the liquid therefrom to the top of the liquid and vapor chamber in said primary circuit, said means also acting to draw the vapor downwardly through said radiator.

10 3. A cooling system for internal combustion engines comprising primary and secondary cooling circuits, the former serving to maintain a circulation of cooling liquid about the engine, and the latter serving to draw off generated vapors from the primary circuit, to condense said vapor and to return the same to said primary circuit in liquid form, said primary circuit including a water 15 hopper with a vapor space at its top, and said secondary circuit including a radiator, a pump and a return pipe, said radiator being connected to the vapor space of said water hopper, and said return pipe extending into the vapor space of said hopper.

20 4. The combination with the cylinders of an engine and a radiator, said cylinders having a water jacket and said radiator having a lower water tank and a closed vapor chamber, a closed water hopper having a vapor space in its top connected to the vapor chamber of said radiator, supply and return circuits, connections between said water jacket and hopper for the circulation of water 25 through said jacket, a pump, a conduit connecting the lower water chamber of said radiator to said pump, and a return pipe connecting the discharge of said pump to the vapor space of said hopper.

30 5. The process of cooling internal combustion engines which consists in providing a liquid cooling circuit about the engine having a liquid and vapor chamber at its upper portion, causing vapor to flow from said chamber downwardly through a 35 radiator to condense said vapor at the lower end of said radiator, and returning the condensed vapor directly to the top of the liquid and vapor chamber aforesaid above the 40 level of liquid therein.

45 6. A cooling system for internal combustion engines comprising a primary cooling circuit including a liquid and vapor chamber at the upper portion thereof; a secondary cooling circuit, the upper end of which 50 communicates with said liquid and vapor chamber above the level of the liquid therein; a radiator included in said secondary circuit and disposed below said vapor chamber; and means for causing vapor to flow from said liquid and vapor chamber downward through said radiator, and for returning condensed vapor from the lower end of 55 said radiator to said liquid and said vapor chamber above the level of liquid therein.

7. In a cooling system for internal combustion engines and in combination with an engine having a jacket through which a cooling liquid may flow, a chamber with which said jacket communicates, and the 60 location of which is such that the normal level of the cooling liquid therein is substantially above the upper end of said jacket and below the upper end of said chamber, so that a vapor space will be provided with 65 in and at the upper end of said chamber, a condenser, the upper end of which is in communication with the vapor space within said chamber, and means for causing vapor to flow from said chamber space downwardly through said condenser, and for returning the condensed and liquidified vapor to said chamber above the normal level of the cooling liquid therein.

75 8. In a cooling system for internal combustion engines including a jacket for said engine, a radiator, a fluid chamber for said radiator, a conduit connecting said chamber with the lower portion of said jacket, a conduit secured in the upper portion of said 80 jacket and extending within said chamber above the liquid level therein and means for circulating the liquid within said system.

90 9. In a liquid cooled engine, a primary 85 cooling circuit including the engine jacket and also including a chamber so positioned that the normal liquid level therein will be substantially above the upper end of said jacket, a pump for circulating liquid through said primary circuit, a secondary cooling circuit including a radiator communicating with said chamber above the liquid level therein, said radiator serving to condense vapors from said chamber, a pump for returning the condensed liquid from said radiator to said chamber at a point above the 95 normal level of the liquid therein.

100 10. In a liquid cooled engine, a primary 100 cooling circuit including the engine jacket and also including a chamber so positioned that the normal liquid level therein will be substantially above the upper end of said jacket, a pump for circulating liquid through said primary circuit, a secondary cooling 115 circuit including a radiator communicating with said chamber above the liquid level therein, said radiator serving to condense vapors from said chamber, and means for returning the condensed liquid from said radiator to said chamber at a point above the 120 normal level of the liquid therein.

11. In a device of the class described, an engine, a water jacket for said engine, a liquid and vapor reservoir at a higher level than said jacket, passages connecting said jacket with said reservoir, a condensing system for condensing vapors and steam generated in said jacket, and independent 125 passages connecting said system with said 130

- 6
- reservoir above the liquid level therein, substantially as shown and described.
12. In a liquid cooled engine having a jacket, a circulating system for the cooling fluid including the engine jacket, a condensing system associated with said circulating system, the discharge end of each of said systems being above the water level therein, substantially as shown and described.
13. A cooling system for internal combustion engines comprising a primary cooling circuit including a liquid and vapor chamber at the upper portion thereof, a secondary cooling circuit, a radiator in said secondary circuit communicating with and disposed below said liquid and vapor chamber, a liquid chamber at the bottom of said radiator, means for returning the liquid from said last named chamber to the top of the liquid and vapor chamber in said primary circuit, and means to vent the air from said liquid chamber at the bottom of the radiator.
14. A cooling system for internal combustion engines comprising primary and secondary cooling circuits, the former serving to maintain a circulation of cooling liquid about the engine, and the latter serving to draw off generated vapor from the primary circuit, to condense said vapor and to return the same to said primary circuit in liquid form, said primary circuit including a water hopper with a vapor space at its top, and said secondary circuit including a radiator, said radiator at its upper end being in communication with the vapor space of said water hopper, a pump communicating with the lower end of said radiator and a return pipe extending upwardly from said pump and terminating in the vapor space of said hopper.
15. A cooling system for internal combustion engines comprising a water hopper with a vapor space at its top, a primary cooling circuit communicating with said water hopper, a pump in said primary circuit, a secondary cooling circuit, a radiator in said secondary circuit, a conduit extending from the upper end of said radiator and terminat-
- ing in the vapor space of said water hopper, 50 a pump connected to the lower end of said radiator, and a return pipe extending upwardly from said last named pump and terminating in the vapor space of said water hopper. 55
16. In a liquid cooled engine having a jacket, a circulating system for the cooling fluid including the engine jacket, a condensing system associated with said circulating system, a water hopper common to said systems and having a vapor space above the liquid level therein, the discharge end of each of said systems terminating in said vapor space above the liquid level in said hopper. 60
17. A cooling system for engines including a primary cooling circuit having a liquid and vapor chamber at its upper portion, a secondary cooling circuit including a condenser communicating with the vapor space 70 of said chamber, means for withdrawing vapor from said chamber through said condenser and returning the condensed liquid to said chamber, and means controlled by the pressure in said chamber for causing 75 liquid to pass from said chamber into said condenser.
18. A cooling system for engines including a primary cooling circuit having a liquid and vapor chamber at its upper portion, a secondary cooling circuit including a condenser, a pipe extending from the vapor space of said chamber to said condenser, means for withdrawing vapor from said chamber through said pipe and said condenser and returning the condensed liquid to said chamber, and means controlled by the pressure in said chamber for causing 80 liquid to pass from said chamber through said pipe into said condenser, said last 85 named means including a cap secured to the upper end of said pipe and extending below the water level in said chamber and having openings above said water level and below said water level, substantially as described. 90

In testimony whereof I affix my signature.
WELLINGTON W. MUIR.
